WRIST WATCH WINDING DEVICE

Edward W. Poltrack, Chicago, Ill.

Application December 20, 1950, Serial No. 201,819

3 Claims. (Cl. 81—7.5)

1

This invention relates to a wrist watch winding device and has for an object to provide an improved device especially useful in winding a small wrist watch, particularly that type of small wrist watch whose winding crown is so small that it is very difficult to grasp it between one's fingers.

A further object of this invention is to provide an improved wrist watch winding device which has a winding member which may be temporarily attached to the winding crown of a wrist watch in proper axial alignment therewith, whereby the winding crown of the wrist watch may be properly wound to the proper tension, and then the device may be easily detached therefrom.

A further object of this invention is to provide a wrist watch winding device accessory of a neat appearance and small size so that it may be kept in a jewel case or other convenient storage space, wherever the wrist watch may be normally stored, as at night, so that it may be handy for quick attachment to the wrist watch for winding it at the usual desired winding time once every twenty-four hours and then detached therefrom and left stored until the next occasion for use twenty four hours later.

This application is a continuation in part of application Serial No. 140,135 filed January 23, 1950, for "Device for Winding Wrist Watches," now abandoned.

With the foregoing and other objects in view, this invention comprises the combination, constructions and arrangement of parts hereinafter set forth, claimed and disclosed in the accompanying drawings, wherein:

Fig. 1 is a plan view of the wrist watch winding device of this invention in operative position;

Fig. 2 is a sectional view taken horizontally through Fig. 1, but showing the winding shaft 40

45 in elevation;

Fig. 3 is a sectional view on line 3—3 of Fig. 2, showing the winding shaft partly in section;

Fig. 4 is a sectional view on line 4—4 of Fig. 2;

Fig. 5 is an enlarged bowl fragment showing 45 the longitudinal ribs.

Fig. 6 is a sectional view on line 6—6 of Fig. 2.

Small wrist watches, particularly of the type used by women, are often very difficult to wind properly due to the extremely small winding crown attached to the minute winding stem of the wrist watch. As a result, in attempting to wind the winding crown, it is often difficult to grasp it with one's fingers due to its smallness and due to its extreme proximity to the side of 55

the watch. It is therefore difficult not only to wind the watch but determine when it has been properly and fully wound, without overwinding the same. With the wrist watch winding device accessory of this invention, these difficulties are eliminated.

The wrist watch winding device 10 of this invention is a very useful accessory for winding a small wrist watch, such as shown at 11. The 10 winding device 10 includes a somewhat elongated yoke 12 which may be provided with a very fine finish, such as gold plate or other suitable finish. The bight 13 of the yoke 12 is provided with an axially extending shaftway 14 through which 15 is journaled the shank 15 of a partially threaded shaft 16, the shaftway 14 and shank 15 being of somewhat reduced diameter compared to the main portion of the threaded shaft 16. A knurled handle 17 is wedged or otherwise secured to the end of the shank 15 at 19 on the outside of the bight 13 of the yoke 12, thereby securing the threaded shaft 16 for rotation through the bight of the yoke 12.

The other end of the threaded shaft 16 is left 25 unthreaded and instead is divided into four somewhat spaced-apart segments 18, each segment 18 terminating in a bowl segment 20 which flares outwardly on its outer surface and is provided with four fine longitudinally extending ribs 29 and also is recessed at 21 on its inner surface. When the bowl segments 18 are released after being pressed toward each other, they will normally tend to return to their spaced-apart position.

35 Threaded about the threaded shaft 16 before its shank 15 is assembled through the yoke bight 13 is an internally threaded sleeve 22, which is externally knurled at 23. However, the internal threads of sleeve 22 extend only about as far as the external threads on shaft 16, and the interior surface of the sleeve 22 is left smooth and unthreaded at its opposite end 24 where such end 24 abuts against the outer surface of the flared bowl segments 20.

As will be apparent, rotation of the knurled sleeve 23 on shaft 16 while holding the shaft 16 against rotation by means of the knurled handle 17 will cause the sleeve 22 to ride over the flared outer surface of bowl segments 20 and press them together when rotated in one direction, and will move away from such bowl segments 20 when rotated in the other direction, permitting their inherent resiliency to restore them to the spaced-apart position.

55 The size of the inside recessed surfaces 21 of

bowl segments 20 is such that the diameter of the bowl provided thereby is greater than the diameter of a wrist watch winding crown when the bowl segments 20 are in their released spaced-apart position, and of a slightly smaller diameter than the wrist watch winding crown when the bowl segments 20 are pressed into tight contact with each other by winding the sleeve 22 fully thereover.

Hence, to attach the shaft to the winding crown 25 of the wrist watch 11, a watch supporting plate 26 is provided, having a pair of sliding fingers 27 at one end thereof intended to slidably embrace the sides of the yoke 12, while at the other end there is a slightly stepped up portion 28 on which the wrist watch 11 will be supported for properly axially aligning the center of the winding crown stem of the wrist watch with the center of the shaft 16.

In operation, the watch 11 is placed on the plate portion 28 while the sleeve 22 is out of contact with the bowl segments 20, and the bowl segments 20 are then placed about the wrist watch crown 25 to embrace the same. Then, while holding the knurled handle 17 with the fingers of one hand, the sleeve 22 is rotated by means of its knurled surface 23 to clamp the bowl segments 20 about the crown of the wrist watch. As soon as it is sufficiently clamped, the grip on the handle 17 is released and continued rotation of the sleeve 23 will thus rotate the crown of the wrist watch and wind the watch. This is continued until the watch is felt to be fully wound, which will be readily apparent to the fingers rotating the same. Then, with the watch fully wound, the sleeve 22 is rotated in the opposite direction while holding the knurled handle 17, thus releasing the pressure on the bowl segments 20 and unclamping the same from the wrist watch crown, whereupon the watch may be removed therefrom and worn.

removed therefrom and worn.

While the device has been shown and the structure described in detail, it is obvious that this invention is not to be considered as being limited to the exact form disclosed, and that changes in detail and construction may be made therein within the scope of what is claimed, without departing from the spirit of this invention.

Having thus set forth and disclosed the nature of this invention, what is claimed is:

1. A wrist watch winding device comprising a yoke, a shaft journaled through the bight of said yoke, knurled handle means secured on said shaft externally of said yoke, said shaft extending axially of said yoke, said shaft having a threaded portion within said yoke at said bight end thereof, the other end of said shaft beyond said threaded portion being divided into a plurality of spaced-apart resilient segmental portions, said segmental portions terminating in outwardly flaring internally recessed bowl portions of a size to fit over and clamp about the crown of a wrist watch to be wound, and means for moving said bowl segment portions to clamping position and for rotating the same when in clamped position, said means comprising an externally knurled sleeve within said yoke about said shaft, said sleeve having an internal thread complementary to the thread on said shaft, and an un-

threaded portion within said sleeve at the other end thereof engaging said outwardly flaring surfaces of said bowl segments to move said bowl segments to clamping position when said sleeve is rotated on said shaft.

5 is rotated on said shaft.

2. A wrist watch winding device comprising a shaft journaled through the bight of said yoke, a knurled handle means secured on said shaft externally of said yoke, said shaft extending axially of said yoke, said shaft having a threaded portion within said yoke at said bight end thereof, the other end of said shaft beyond said threaded portion being divided into a plurality of spaced-apart resilient segmental portions, said 10 segmental portions terminating in outwardly flaring internally recessed bowl portions of a size to fit over and clamp about the crown of a wrist watch to be wound, and a partially internally threaded sleeve on said threaded shaft portion having an unthreaded end engaging said outwardly flaring bowl segment portions for moving said bowl segment portions to clamping position and for rotating the same when in clamped position, and means mounted on said 15 yoke for detachably supporting said wrist watch winding device in axial alignment with the wrist watch crown.

watch crown.

3. A wrist watch winding device comprising a U-shaped yoke, a shaft journaled through the bight of said yoke, knurled handle means secured on said shaft externally of said yoke, said shaft extending axially of said yoke, said shaft having a threaded portion within said yoke at said bight end thereof, the other end of said shaft beyond said threaded portion being divided into a plurality of spaced-apart resilient segmental portions, said segmental portions terminating in outwardly flaring internally recessed bowl portions of a size to fit over and clamp about the crown of a wrist watch to be wound, and a partially internally threaded sleeve on said threaded shaft portion having an unthreaded end engaging said outwardly flaring bowl segment portions for moving said bowl segment portions to clamping position and for rotating the same when in clamped position, and means mounted on said yoke for detachably supporting said wrist watch winding device in axial alignment with the wrist watch crown, said latter means comprising a plate having oppositely disposed inturned fingers thereon at one end thereof slidably embracing the sides of said yoke, said plate being adapted to support the wrist watch thereon with its crown in axial alignment with the axis of said clamping bowl and winding shaft.
